UNITED STATES PATENT OFFICE.

ISAAC A. HARDY, OF EVANSVILLE, INDIANA.

CIGAR-BANDING MACHINE.

1,292,409.

Specification of Letters Patent. Patented Jan. 21, 1919.

Application filed December 10, 1917. Serial No. 206,437.

To all whom it may concern:

Be it known that I, ISAAC A. HARDY, a citizen of the United States, residing at Evansville, county of Vanderburg, and State of Indiana, have invented certain new and useful Improvements in Cigar-Banding Machines, of which the following is a specification.

This invention relates to cigar banding machines.

In machines of the class to which my invention relates difficulty has heretofore been experienced in applying the band or label around the cigar without crushing or abrading the wrapper of the latter and in so feeding the cigars to the banding mechanism that they will be banded, one at a time, without likelihood of choking or clogging the operative parts of the machine. It is impossible to make a large number of cigars of precisely the same dimensions although they may approximate those dimensions. In machines heretofore known to the art the banding mechanism has not, so far as I am aware, been adapted to automatically compensate for the slight irregularities or differences in shape or dimensions of the cigars, resulting in either the imperfect application of the band, in some instances, or the damaging of the cigars by crushing them or abrading their wrappers, in other instances.

My object is to provide a cigar banding machine which will automatically feed the bands, one at a time, from a hopper to a carrier, position them in pockets or holders, retain them in the holders by vacuum, feed the cigars, one at a time, to the pockets or holders containing the bands, automatically fasten or lay the free ends of the bands around the cigar in overlapped relation, and finally discharge the banded cigars from the carrier. The bands may be of the gummed variety and moistened by improved means, or, they may be devoid of adhesive, and an adhesive-applying means of improved form employed for the application of the adhesive thereto.

In connection with my improvements I provide mechanical operating devices whereby the parts are so timed that they coördinate to effect the sequence of operations, beginning with the initial feeding of a band to a holder of the cigar carrier and ending with the discharge of the completely banded cigar. To that end, I provide cams, levers,

cranks, locking devices, and other instrumentalities, which, while peculiarly adapted to cause the timing and coördination of the parts as aforesaid, are susceptible of modification and I do not limit myself to the precise form, construction and arrangement of these mechanical operating devices, except where specified in the claims.

The band-holding hopper and feeder of my invention embodies novel means for taking off a band from the stack and holding the balance of the stack in such manner that there will be no interference with the take-off of a single band therefrom. There is a take-off slide having a hump or ridge and whose face is subject to vacuum so that the lowermost band of the stack adheres thereto and is so arranged that a space is created below the stack. As the slide advances to deliver the band, novel stack-supporting means enters the space and supports the balance of the stack, said means being so coördinated with the slide that there is no interference between them. The band is delivered to a pair of rollers which feed it forward, on the retraction of the take-off slide, the vacuum having been released. A clamping device then grasps the rear end of the band.

The cigar carrier, which is shown in the form of a rotary wheel or drum, is timed and operated for a step-by-step movement, being first positioned so that a pocket or holder will be brought into position for the band to be pressed into said pocket, immediately after said band has been delivered by the slide. A suitably timed pressing device then acts to force the band into the pocket or holder. The pocket or holder is subject to vacuum and the band is thus held therein. On the next advance movement of the cigar carrier, the pocket or holder which has previously received a band, is brought into position to receive a cigar.

The cigar feeder comprises a hopper or trough having a step-by-step traveling apron at its bottom on which the cigars rest. Improved mechanism causes the apron to advance with a step-by-step motion, there being a gate or cut-off which lets through only a single layer of cigars from the hopper as they approach the point where they are to be delivered to the cigar carrier. The feeding device insures the delivery of but a single cigar to the pocket of the cigar carrier which has the band. To insure the proper position-

ing of the cigar against the band in the pocket, a presser gently yet firmly presses the cigar into the pocket.

After the band has been pressed into a 5 pocket of the cigar carrier, and before the cigar carrier has advanced to cigar-receiving position, an improved moistener acts on the advance end of the band. If the band is not a gummed one, there will be substituted an 10 adhesive applying device for the moistener hereinafter shown and described. Consequently the band which is held in the pocket of the cigar carrier by a vacuum acting thereon, is both positioned and conditioned 15 to be wrapped around the cigar by the novel wrapping mechanism.

The object of my band wrapping mechanism is to first press the rear end of the band down on and around the cigar and to hold 20 it there; then to finish the movement by a tucking action accomplished, in the present instance, by an advancing tucker or folder which snugly and evenly lays the extreme rear end of the band down on the cigar. 25 The wrapper and tucker then retreat and a follower advances across the mouth of the pocket, rolling down the band on the cigar and holding the cigar in the pocket until, by further step-by-step movement of the carrier, the banded cigar is brought to a point 30 where it is to be discharged, whereupon the follower and holder releases the cigar and the latter falls out onto a conveyer which takes it off.

35 The wrapping and tucking or finishing devices are arranged to yield against spring pressure so that they cannot injure the cigar. Heretofore great difficulty has been experienced in that part of a cigar-banding machine which actually folds or wraps the ends 40 of the band. My improvements provide for a light, yet sufficient, pressure of the wrapping device, without permitting it to dig into the cigar. By the use of a wrapping 45 device which comprises an initially acting member that forces the band down on and around the cigar, and a secondary wrapping device which acts thereafter to finish the wrapping action, I prevent injury to the 50 cigar and insure tight and even application of the band thereto. The moistened or gummed end of the band is then pressed down, as the wrapping and tucking devices retreat, by the follower and holder.

55 Other features of the invention will appear more fully hereinafter.

The invention being susceptible to modifications in various respects without departing from its essential principles, the disclosure hereinafter given is to be considered 60 illustrative, rather than restrictive, of the scope of the invention.

In the accompanying drawings—

Figure 1 is a side elevation, the moistening 65 pan being broken away;

Fig. 2 is a longitudinal section;

Fig. 3 is a side elevation opposite to Fig. 1;

Fig. 4 is an enlarged detail section, showing the successive steps of feeding a band, 70 positioning it for pressing into a pocket, and placing a cigar on the band, in the pocket, prior to the actual folding or wrapping operation.

Fig. 5, a detail plan view of the band 75 hopper and adjacent mechanism, the stack of bands being shown in dotted lines.

Fig. 6 is a view like Fig. 4, but showing the manner in which the band is pressed into its pocket and moistened, and the initial 80 operation of the wrapping mechanism.

Fig. 7 is a detail view of the device for gripping the rear end of the band when it is being forced into the pocket.

Fig. 8, a detail side elevation of a portion 85 of the band hopper showing mechanism for lifting the stack of bands.

Fig. 9, an enlarged detail view showing the operation of the mechanisms during the 90 actual banding of the cigar.

Fig. 10 is a detail front view of one of the followers and holders.

Fig. 11, a longitudinal section there- 95 through.

Fig. 12, a detail view showing the manner 100 in which the cigar is held and is released, after banding.

Fig. 13 is an enlarged detail vertical section through the cigar holding drum or carrier and the vacuum chest.

Fig. 14 is a front view of the vacuum 105 chest.

Fig. 15, a plan view thereof.

Fig. 16, an enlarged detail view showing the operation of the cigar feeder and cut-off, 110 and the cigar presser.

Fig. 17, a detail plan view of the cigar 115 feeder and cut-off.

Fig. 18, a detail front elevation of the cigar chute.

Fig. 19, a detail plan view, partly in section, showing the cigar carrier locking device.

Fig. 20, a detail front elevation of the 115 band folding or wrapping mechanism.

Fig. 21, a side elevation thereof.

Fig. 22, a detail view of the lifting finger of the band wrapping device.

Fig. 23, a detail side elevation of the moistening device, shown in raised position, 120 dotted lines illustrating its action.

Fig. 24, a detail of the operating mecha- 125 nism therefor; and

Fig. 25, a detail view of the operating means for the followers and cigar retainers.

The operative parts are supported by frame 1. The shaft 2 is the master shaft which initiates the operation of the various mechanisms and, mainly, controls the timing thereof, although certain mechanisms 130

are timed by the countershaft 3, the latter being connected by a sprocket chain 4 to the shaft 2. The cigar carrier or drum 5 is secured to a shaft 6 and is turned with a step-by-step movement from shaft 2 by a Geneva stop movement comprising the wrist wheel 7 on shaft 2 and the stop wheel 8 on shaft 6. The cigar carrier is turned one step during each rotation of the shaft 2. To lock the cigar carrier in its different positions, as it turns in a step-by-step manner, there is provided a spring actuated latch 9 which is adapted to enter the inter-dental spaces between the teeth of the stop wheel 8 and is provided with an arm 10 which has a roller arranged to be engaged by a cam 11 on the wrist wheel 7 for the purpose of retracting the locking device just prior to the engagement of the wrist pin 12 with the stop wheel 8.

The hopper 13, which contains the cigars to be banded, has an endless apron 14 running across its bottom, lengthwise thereof, around drums 15 and 16. The drum 15 carries a ratchet wheel 17 with which co-operates the pawl of a rockable lever 18. The lever 18 is connected to a rocker 19 by a rod 20; rocker 19 is operated from the shaft 2 by rod 21 and eccentric 22. Each rotation of the shaft 2 causes a slight advance of the apron 14. A spring actuated idler drum 23 takes up the slack in the lower stretch of the apron 14.

A rocking gate 24 which is operatively connected to the rocker 19 by a crank and link 25, is adapted to hold back the layers of cigars in the hopper and to allow only the lower layer to advance to the delivery chute 26 down which the cigars pass for delivery, one at a time, to the cigar carrier or drum.

At the bottom of the chute 26 is a rockably mounted gate 27, Figs. 2, 4, 6, 16 and 17, which supports a few of the cigars and, when rocked, allows the lowermost cigar to fall by gravity in a horizontal position into one of the pockets of the cigar carrier. When the gate 27 turns to allow the cigar to fall into the pocket in the carrier, the curved cut-off fingers 28 support the remaining cigars in the chute, as shown in Fig. 16. On return of the gate to the normal position of Figs. 4 and 6, the curved fingers 28 are withdrawn from the chute and the gate supports the cigars. The end of the chute is provided with downwardly extending fingers 29, Fig. 18, which, in connection with the fingers on the gate 27, insure that the cigar is directed to the pocket in the carrier, as shown in Fig. 16. The gate 27 is periodically operated by the means shown in detail in Fig. 16 comprising a cam 30 on counter-shaft 3, a slidably pusher rod 31 having a roller co-operating with the cam, a spring 32 which keeps the roller in en-

gagement with the cam, and a link 33 connecting the rod 31 to a crank 34 on the gate 27.

To insure the pressing down of the cigar into the pocket in the carrier or drum, there is provided a presser finger 35, Figs. 6, 16, which is carried by a rock shaft 36 having a crank 37 provided with a pin 38 received in a fork 39 of a lever 40 pivoted at 41 and pulled by a spring 42 to keep the finger 35 normally raised. A cam 43 on counter-shaft 3 tucks against the other end of the lever 41 after the cigar has fallen into the pocket in the carrier, and thereby presses the finger 35 down on the cigar, as shown in the position represented in Fig. 4.

The cigar carrier 5 is provided with a plurality of cigar receiving pockets 44 which are spaced at equal distances apart around the periphery thereof. Leading to each pocket is a port 45, Figs. 6 and 13, all of the ports opening into an annular channel 46. Located on the shaft 6 is a bracket 47 which may be suitably secured so that it will be stationary; it could be connected to the frame 1. Carried by this bracket is an arc-shaped shoe 48 which is received in the channel 46 and is held yieldingly thereagainst by springs 49; screws 50 support the shoe from the bracket 47. The shoe has an arc-shaped channel 51 in its face which is adapted to simultaneously communicate with two of the ports 45. A pipe 52 connected to the shoe 48, communicates with the channel 51 and constitutes means whereby vacuum may be provided in the ports 45. The ports 45 may have as many outlets or mouths, leading to the pockets 44, as desired to suitably hold the cigar band 53 in said pockets, once said band has been located there, as shown, for instance, in Fig. 6. After the cigar has been banded, the vacuum is broken by the passage of the port 45 away from the influence of the channel 51 as the cigar is held by the follower and holder thereafter.

Preferably, the carrier 5 is provided with a supplemental ring 5^a having notches 5^b to receive the cigar so that the latter will be supported at two points as shown in Fig. 13. The ring 5^a is connected to the carrier 5 in any suitable manner as, for instance, by bolts 54.

The carrier 5 is provided with slots 55 which communicate with the sides of the pockets 44. The followers and holders 56 are normally located in the slots 55, in retracted or retreated position, as shown in Fig. 6, as they are not advanced until the cigar has been placed in the pocket 44 and the rear end of the band 53 has been folded down, held, and tucked. Thereafter the follower 56 is made to advance as shown, for instance, in the two positions at the left of Fig. 9. The follower remains in the last

position at the left of Fig. 9 after the cigar has been completely banded, holding the cigar in the pocket 44 as the carrier 5 continues its step-by-step returning in the direction of the arrow and until the pocket is at the extreme lowermost position, as shown at the bottom of Fig. 12, whereupon the follower 56 is withdrawn into the slot 55 to remain there during the balance of the rotation of the carrier 5 until the latter can assume the next to the last left hand position of Fig. 9. The followers 56 are of the construction shown in Fig. 10, being provided with a roller 57 which is of sufficient width to properly cooperate with the band 53. The follower is pivotally mounted on a bolt 58 and is pressed by a spring 59 coiled around the bolt 58, the action of the spring being such that the roller 57 is held against the inner margin of the slot 55 and is pressed in a direction which will cause the roller to bear down upon the gummed and moistened or advance, end of the band 53, as shown in the two left hand, positions of Fig. 9. The spring also holds the follower down in the pocket 44 to retain the cigar in the pocket until it reaches the lower position in Fig. 12. The bolts 58 are carried by bell crank levers 60 pivoted to the carrier at 61 and provided with rollers 62 which travel on a cam 63, the latter being secured to the frame 1. The rollers run on the low part of the cam except from the point where the cigar is completely banded to the next to the lowest position at the left of Fig. 12; they travel on the high or dwell portion of the cam from the point where the cigar is banded to where it is about to be released, as will be clear from Figs. 9 and 12. The cam does not, however, cause operation of the bell crank lever 60 to effect the folding down of the gummed and moistened, or advanced, end of the band 53. Each bell crank lever 60 is actuated by a coil spring 64 which holds the roller 62 against the cam and causes the follower 56 to retreat into its slot 55 when the roller 62 passes onto the low part of the cam 63.

The followers are made to advance from their slots 55 by positively acting means such as shown in Figs. 9 and 25. On the shaft 2 is a cam 65 which operates a pusher rod 66, slideable in a sleeve 67 secured to the frame 1 by a bracket 68 and retracted by a spring 69 to keep the roller 70 in engagement with the cam 65. The pusher rod 66 has a foot 71 which is arranged to engage the roller 62 of that one of the bell crank levers 60 which corresponds to the pocket 44 into which the cigar has been dropped, so that after the rear end of the band 53 has been folded down and tucked, the follower 56 will be made to fold down the gummed and moistened, or advance, end of the band, as shown in the second position from the left of Fig. 9.

Suitably secured to the frame 1, by a

bracket 72 is an upright band hopper 73 in which the bands 74 are arranged in a stack, Figs. 4 and 6. The bottom of the hopper 73 comprises a slideable feeder 75 which is hollow as at 76 and has ports 77 leading to its upper face. Through a nipple 78 and a flexible tube 79, the hollow interior 76 is subject to vacuum from any suitable source. The feeder 75 is provided with a short rack 80 and is retracted by a spring 81. A shaft 82 carries a gear segment 83 adapted to mesh with the rack 80 to advance the feeder 75. When the segment 83 disengages from the rack 80, the spring 81 snaps the feeder 75 back to the normal position shown in Fig. 4. The shaft 82 is provided with a gear 84 which meshes with the gear 85 on the counter shaft 3. The feeder 75 has a hump 86 which causes the lowermost band 53 to assume the form shown in Figs. 4 and 6 and enables the vacuum, acting through ports 77, to draw down the end portions of the band away from the remaining bands of the stack 74, thus providing a space 87, which is eventually increased in height by means now to be described. The vacuum causes the band to adhere to the feeder 75 so that it can be taken off the bottom of the stack without pulling other bands with it. To elevate the advance end of the stack 74 there is provided a pivoted arm 88 which is pressed down by a spring 89 and carries a cross pin 90 which normally lies in the position shown in Fig. 4 but is elevated to the position shown in Fig. 6 by a cam 91 on the shaft 82 prior to the advance of the feeder 75 so that the stack 74 will be elevated to permit the feeder to advance, as shown in Fig. 6. To hold the stack 74 in elevated position there is provided the mechanism shown in Fig. 5 consisting of rockers 92, 93, inter-geared at 94 and pivoted at 95 which have fingers 96 adapted to enter the space 87 as the feeder 75 advances. The fingers 96 are so arranged that the rocking of the rockers 92, 93 prevents the fingers from interfering with the hump 86. A spring 97 cooperating with a pin on the rocker 93 keeps them normally retracted. The rockers are advanced to position the fingers 96 in the space 87 by the co-operation of a cam 98 with the rocker 93, said cam being carried by the shaft 3.

The feeder 75 delivers the band 53 to a pair of feed rollers 99, or to a feed roller, Figs. 4 and 6. The feed roller or rollers grasp the advance end of the band 53 and continue to feed it on the retraction of the feeder slide 75. The feed roller 99 is carried by a shaft 100 which has a gear 101, Fig. 2, meshing, by means of gears 102, with a gear 103 on the shaft 82. To hold the rear end of the band 53 after it has been fed forward by the roller 99, in the manner shown in Fig. 6, there is provided the clamping lever 104 shown in Figs. 4, 5, 6 and 7, said

lever being pivoted at 105 and having an arm 106 which is adapted to press the end of the band down on the plate 107, Fig. 6. The lever 104 is released by a spring 108 and 5 is actuated by a cam 109 on the shaft 82, the cam being set and timed to act only after the band 53 has been fed forward by the roller 99 completely across the mouth of the pocket 44. The clamping lever 104 is 10 provided to insure against the release of the band by the roller 99 before the band has been pressed into the pocket 44. The lever 104 insures that the rear end of the band be tightly held to enable the free part 15 of the band, bridging the pocket 44, to be pressed down into the pocket.

Referring to Figs. 4, 5 and 6, there is shown at 110, pivoted to the frame 1, a lever 111 which is adapted to be operated by a 20 cam 112 on the shaft 3. Pivoted at 113 to the other end of said lever is an arm 114 which is pressed by a spring 115, anchored at 116. The spring holds the arm 114 against a lug 117 on the lever 111. The arm 25 114 carries a stud 118 on which is journaled a presser roller 119 which is preferably of rubber. A spring 120 holds the lever 111 normally in the position shown in Fig. 4. The cam 112 is so timed that after the band 30 53 has been fed across the mouth of the pocket 44 and the arm 106 has clamped the rear end of the band against the plate 107, said cam 112 will cause the roller 119 to be pressed down, forcing the band 53 into the 35 pocket 44 and against the wall thereof. The port 45 is at that time subject to vacuum and consequently the band will be retained by the vacuum in said pocket, as shown in Fig. 6. Further rotation of cam 112 permits 40 spring 120 to elevate roller 119 to the position shown in Fig. 4.

Reference being had to Figs. 1, 23 and 24, there is a pan or reservoir 121, suitably carried by the frame 1, which may contain 45 either water or a fluid adhesive, according to whether the bands in the stack 74 are gummed and only need to be moistened, or, require the application of an adhesive. A bracket 122 secured to frame 1 serves as 50 a bearing for a band wheel 123 to whose shaft 124 is connected a ratchet wheel 125. A bell crank 126 is pivoted at 127 to the bracket 122 and carries on one of its arms a pawl 128 which is adapted to engage the ratchet wheel 125. At the end of the other 55 arm of the bell crank is a grooved foot 129. An endless tape or band 130 passes around the pulley 123 and foot 129 and other idler pulleys 131, 132. A lever 133 pivoted at 60 134, is connected by link 135 to the bell crank 126 and is operated by a cam 136 on the shaft 2, a spring 137 holding the lever against the cam.

The cam 136 is so timed that it causes the 65 bell crank 126 to operate with, or imme-

dately after, the cam 112 causes the lever 111 to force the roller 119 into the pocket 44. Consequently the moistening tape 130 is pressed down upon the free or advance end of the band 53 immediately the roller 70 119 has forced the band 53 into the pocket 44, as shown in Fig. 6, whereby the band is moistened substantially simultaneously with the pressing of the band into the pocket. On the descent of the foot 129 to 75 moisten the band 53, the ratchet 128 drags back over the ratchet wheel 123 so that on the elevation of the foot 129, the tape 130 will be shifted slightly to bring a fresh moistened part thereof under the foot 129 80 for application to a succeeding band 53.

Referring now to Figs. 3, 4, 6, 9, 20, 21 and 22 in connection with the novel means for folding, holding, and tucking the band, there is a shaft 138, to the outer end of 85 which is secured an arm 139 which is operated by a slideable rod 140 having a roller 141 coöoperating with the cam 142 on shaft 3. A spring 143 retracts the arm 139 and turns the shaft 138 backwardly. Loose on 90 the shaft 138 is an arm 144 which carries the folder and holder 145. Secured to the shaft 138 and located alongside the arm 144 is an arm 146 which carries the tucker 147. A slot-and-pin connection 148 enables the 95 arms 144 and 146 to have relative movement which permits the arm 146 to advance after the arrest of the arm 144 so that the tucker 147 will slide along the top of the folder and holder 145 and move beyond it, as 100 shown in Fig. 9. Thus, the folder and holder 145, having entered the pocket 44 and engaged the rear end of the band 53 and pressed it down on the cigar, holds the band against the cigar while the tucker 105 147 continues to advance with the continued turning of the shaft 138, enabling the tucker to complete the folding or wrapping of the rear end of the band 53. To arrest the arm 144 there is provided an adjustable screw 110 149 which is carried by the frame 1. A spring 150 connects the arm 144 to a bracket 151 on the arm 146, said spring drawing the arm 144 forward to bring the end of the slot against the pin at 148. The two arms 115 144 and 146 move as a unit to a point beyond the position shown in Fig. 6, and until the holder and folder 145 has pressed the band 53 down on the cigar and is holding it thereagainst. The arm 144 then engages 120 the screw 149 and the continued turning of the shaft 138 causes the arm 146 to continue its advance so that the tucker 147 slides along the top of the holder 145 and tucks down the end of the band 53. The 125 tucker 147 is pressed down on the holder 145 by a spring 152 which also presses the holder 145 down so that the latter is also under spring pressure. To elevate the holder 145 and with it the tucker 147 when 130

they are on their return movement, there is provided a dog 153 whose head has a pin 154 which underlies the holder 145 and whose tail is adapted to engage a lug 155, shown by dotted lines in Figs. 4 and 6, projecting from the frame 1. The engagement of the tail of the dog 153 is shown in Fig. 4, this being the normal position of the holder and tucker.

- 10 General operation: The vacuum feeder 75 draws the lowermost band 53 down from the stack 74 and causes it to conform to the upper surface of the feeder, as shown in Fig. 4. The elevation of the pin 90 from the position shown in Fig. 4 causes the stack 74 of bands to be elevated, thus widening the space 87. The rockers 92, 93 now enter the space 87 and support the stack 74 as the feeder 75 advances from the position shown in Fig. 4 to that of Fig. 6 and farther to the left. The path of movement of the finger 96 of rocker 92 is the same as the feeder 75 and consequently there is no interference with the hump 86. The forward end of the band having reached the feed roller 99, the latter continues to advance the band, the feeder 75 meanwhile being snapped back by the spring 81. The feed roller 99 advances the band 53 across the mouth of the pocket 44 which is now in position to be subject to vacuum. The advance of the band 53 continues until the finger 106, through the operation of the cam 109, is brought down on the rear end of the band to clamp it against the plate 107. It matters not whether at this time the rear end of the band is engaged by the roller 99 as it is firmly held by the finger 106, as shown in Fig. 6. The cam 112 now causes the roller 119 to press the band 53 down into the pocket 44 and the vacuum exercised through port 45 then causes the band to conform to the pocket. The band is held by the vacuum until the cigar 156 is inserted in the pocket and, indeed, until the cigar has been completely banded and removed from banding position. At about the time the roller 119 presses the band into the pocket 44, the foot 129 comes down and presses the tape 130 against the forward end of the band, the latter being backed up by the edge of the carrier 5, as shown in Figs. 6, 23. The turning of the cams 112 and 136 cause the elevation of the roller 119 and foot 129. The locking mechanism shown in Fig. 19 holds the carrier 5 rigid while the aforesaid parts are performing their functions, and said carrier is also held at each arrest of the carrier 5. The next step in the rotation of the carrier 5 brings the pocket 44 into position where the cigar 156 can be allowed to drop thereinto upon the tilting of the gate 27 by the action of the cam 30, Fig. 16. The presser

finger 35 then follows down and presses the 65 cigar into the pocket and against the band, as shown at the left of Fig. 4, and afterward rises and the gate 27 is swung back to the position shown in Fig. 6. The arms 144 and 146 which up to this time have 70 stood in the position shown in Fig. 4 now begin to advance as shown at the left of Fig. 6. These arms advance as a unit, by the swinging of the arm 139 by cam 142, Fig. 3. The rear end of the band 53 is first 75 engaged by the folder and holder 145 and folded or wrapped down on the cigar. The movement continues until the folder 145 reaches the position shown in Fig. 9 where it is arrested by the engagement of the 80 screw 149 with the arm 144. The band is thus held firmly on the cigar with the end of the band protruding beyond the holder. The continued turning of the shaft 138 causes the arm 146 to continue to advance, 85 causing the tucker 147 to slide along the top of the holder 145 and tuck or fold down the extreme end of the band against the cigar. The coöperation of the folder and holder 145 and the tucker 147 prevents 90 damage to the cigar and also the curling up of the rear end of the band 53. At this point the pusher foot 71 engages the roller 62 on the bell crank lever 60 and the follower 56 is made to advance toward the 95 tucker 147, the roller 57 rolling down the forward, moistened, end of the band 53. This movement continues as fast as the holder 145 and tucker 147 retreat, which they then proceed to do, whereupon the 100 moistened end of the band is wrapped down upon the folded, or inner, end thereof and the band is completed around the cigar. The follower 56, after effecting the final 105 folding of the band, as shown in Fig. 9, remains in engagement with the folded ends, causing them to properly adhere and preventing the cigar from falling out of the pocket 44. When the pocket finally reaches the lowermost position, as shown in 110 Fig. 12, the spring 64 retracts the folder 56 and the cigar drops out onto any suitable conveyer 157 which takes it off.

What is claimed is:

1. In a cigar banding machine, the combination with a cigar carrier adapted for a step by step movement and having a plurality of holders for bands and cigars, means for holding and tucking an end of the band in each holder when it reaches a given point of the step by step movement aforesaid, comprising a folder and holder which initially lays and holds an end of the band, and a tucker which acts after the folder to tuck down the projecting held 125 end of the band.
2. In a cigar banding machine, the combination with a cigar carrier adapted for a

- step by step movement and having a plurality of holders for bands and cigars, means for holding and tucking an end of the band in each holder when it reaches a given point of the step by step movement aforesaid, comprising a folder and holder which initially lays and holds an end of the band, a tucker which acts after the folder to tuck down the projecting held end of the band, and a follower which advances in a direction opposite to that of the folder and tucker and lays the other end of the band on top of the folded and tucked end thereof as the tucker retreats.
5. In a cigar banding machine, means for banding a cigar, comprising a movable folder and holder, a movable tucker, and means for causing said folder and tucker to move as a unit during part of their travel and, also, independently of each other during another part of their travel.
10. In a cigar banding machine, means for banding a cigar comprising a movable folder and holder, a movable tucker, and means for causing said tucker to advance beyond the folder and holder for the purpose of tucking down the end of the cigar band which is held by said folder and holder.
15. In a cigar banding machine, means for banding a cigar comprising a movable folder and holder, a movable tucker, and means for causing said tucker to move in the same direction as the folder and holder and to slide over the folder and holder after the arrest of the latter, for the purpose of tucking down the end of the cigar band which is held by said folder and holder.
20. In a cigar banding machine, means for banding a cigar, comprising a movable folder and holder, a movable tucker, and means for causing said folder and tucker to move to and fro as a unit, during a part of their travel and said tucker to move after the arrest of the folder and holder for the purpose of tucking down the end of the cigar band which is held by said folder and holder, said means causing the tucker to retreat before the folder and holder retreats.
25. In a cigar banding machine, means for banding a cigar, comprising a movable folder and holder, a movable tucker provided with spring means for pressing it down on the folder and holder, and means for causing said tucker to move in the same direction as the folder and holder and to slide upon and hold down the folder and holder and to advance beyond the latter for the purpose of tucking down the end of the cigar band which is held by said folder and holder.
30. In a cigar banding machine, the combination with means for holding and tucking an end of the band, comprising a folder and holder which holds an end of the band, and a tucker which tucks down the held end of the band, of a follower adapted to fold down the other end of the band, and mechanism timed to cause the folder and holder and the tucker to advance together in one direction, the folder and holder to engage, fold down, and hold an end of the band, the tucker then to still further advance and tuck down the held end of the band, the tucker to retreat, and the follower to advance in the opposite direction to fold down the other end of the band as fast as the tucker retreats, and the folder and holder then to retreat, with the tucker, from folding and tucking position.
35. In a cigar banding machine, the combination with a cigar carrier having a step by step movement and a plurality of holders for bands and cigars, of means for positively introducing a band in bent or arched condition in a holder when the holder is in one position, vacuum means for holding the band in that condition in the holder while the carrier advances to position the holder
- tucks down the held end of the band, of a separately mounted folder and follower which lays down the other end of the band.
9. In a cigar banding machine, the combination with means for holding and tucking an end of the band, comprising a folder and holder which lays and holds an end of the band, and a tucker mounted separately from the folder, which tucks down the held end of the band, of a folder and follower which lays down the other end of the band and advances to complete the overlapping of the said end on the tucked end of the band as the tucker retreats.
10. In a cigar banding machine, means for holding and tucking an end of the band, comprising a folder and holder and a tucker, the tucker being mounted separately from the folder and adapted to operate over the folder and holder, and means adapting the folder and holder to first lay and hold an end of the band on a cigar and to cause the tucker to move beyond the holder and folder to tuck down the held end of the band.
11. In a cigar banding machine, means for holding and tucking an end of the band, comprising a folder and holder and a tucker, the tucker being adapted to operate over the folder and holder, and means adapting the folder and holder to first move to lay and hold an end of the band on a cigar and to cause the tucker to afterward move beyond the holder and folder to tuck down the held end of the band, said holder and tucker being adapted to move as a unit when moving toward, or away from, holding and tucking position.
12. In a cigar banding machine, the combination with means for holding and tucking an end of the band, comprising a folder and holder which holds an end of the band, and a tucker which tucks down the held end of the band, of a follower adapted to fold down the other end of the band, and mechanism timed to cause the folder and holder and the tucker to advance together in one direction, the folder and holder to engage, fold down, and hold an end of the band, the tucker then to still further advance and tuck down the held end of the band, the tucker to retreat, and the follower to advance in the opposite direction to fold down the other end of the band as fast as the tucker retreats, and the folder and holder then to retreat, with the tucker, from folding and tucking position.
13. In a cigar banding machine, the combination with a cigar carrier having a step by step movement and a plurality of holders for bands and cigars, of means for positively introducing a band in bent or arched condition in a holder when the holder is in one position, vacuum means for holding the band in that condition in the holder while the carrier advances to position the holder

for the reception of a cigar, and means for securing the ends of the band around the cigar after the latter has been placed in the holder and the carrier has advanced to banding position.

14. In a cigar banding machine, the combination with a cigar carrier having a step by step movement and a plurality of holders for bands and cigars, of means for positively introducing a band in bent or arched condition in a holder when the holder is in one position, vacuum means for holding the band in that condition in the holder while the carrier advances to position the holder for the reception of a cigar, means for conditioning the band so that it will adhere when the cigar is banded, and means for folding the ends of the band around the cigar after the latter has been placed in the holder when the carrier is in banding position.

15. In a cigar banding machine, the combination with a cigar carrier having a step by step movement and a plurality of holders for bands and cigars, of means for positively introducing a band in bent or arched condition in a holder when the holder is in one position, vacuum means for holding the band in that condition in the holder while the carrier advances to position the holder for the reception of a cigar, means for clamping or holding an end of the band when the latter is being positively introduced in the holder, and means for applying the ends of the band around the cigar after the latter has been placed in the holder at an advance position of said holder.

16. In a cigar banding machine, the combination with a carrier adapted to move step by step which is provided with a plurality of holders for bands and cigars and has vacuum means for retaining the bands in the holders when said bands are placed therein, of means acting when the holder is in one position, for positively forcing or pressing the bands into the holders to position them so that they will conform to the holders and be retained by the vacuum acting on the holders, and means for banding the cigars after they have been placed in the holders against the bands.

17. In a cigar banding machine, the combination with a cigar holder which is subject to vacuum for holding a cigar band therein, of means for positively pressing or forcing the band into the holder so that it will be arranged for the vacuum to retain it therein, means for conditioning the band so that it will adhere to the cigar, said means acting just after the forcing of the band into the holder, and means for banding the cigar after it has been placed in the holder and against the band.

18. In a cigar banding machine, the combination with a movable cigar carrier hav-

ing a plurality of holders for the bands and cigars and provided with vacuum means for retaining the bands in the holders, of means for forcing or pressing the bands into and substantially conforming to the holders when the latter are in a predetermined position of the step by step movement of the carrier, means for holding or clamping one end of the band while it is being thus pressed or forced into the holder, means for conditioning the band so that it will adhere to the cigar, said means acting when the band is in the holder and prior to the entry of the cigar therein, and means for banding the cigar at another position of the holder in the step by step movement of the carrier, after the cigar has been placed in the holder and against the band.

19. In a cigar banding machine, the combination with a movable cigar carrier having a plurality of holders for the bands and cigars and provided with vacuum means for retaining the bands in the holders, of means for forcing or pressing the bands into and substantially conforming to the holders when the latter are in a predetermined position of the step by step movement of the carrier, means for holding or clamping one end of the band while it is being thus pressed or forced into the holder, means for conditioning the band so that it will adhere to the cigar, said means acting when the band is in the holder and prior to the entry of the cigar therein, means for automatically feeding a cigar to the holder and pressing it into said holder against said band, and means for banding the cigar after it has been thus fed and pressed into the holder.

20. In a cigar banding machine, the combination with a cigar carrier which is adapted to advance step by step and is provided with a plurality of holders for the bands and cigars and has vacuum means acting on said holders to retain the bands therein, of a band hopper, means for taking off the bands from said hopper, one at a time, and disposing them across the holder, means for positively forcing or pressing the band into the holder to cause it to substantially conform to the latter, said vacuum means retaining the band in the holder, and means for folding the band around the cigar after the latter has been forced in the holder.

21. In a cigar banding machine, the combination with a cigar carrier which is adapted to advance step by step and is provided with a plurality of holders for the bands and cigars and has vacuum means acting on said holders to retain the bands therein, of a band hopper, means for taking off the bands from said hopper, one at a

- time, and disposing them across the holder, means for clamping or holding one end of the band so that the intermediate part of the band may be forced into the holder, 5 means for positively forcing or pressing the band into the holder, said vacuum means retaining the band in the holder, and means for folding the band around the cigar after the latter has been placed in the holder.
- 10 22. In a cigar banding machine, the combination with a cigar carrier which is adapted to advance step by step and is provided with a plurality of holders for the bands and cigars and has vacuum means 15 acting on said holders to retain the bands therein, of a band hopper, means for taking off the bands from said hopper, one at a time, and disposing them across the holder, means for holding the rear end of the band 20 so that the band may be positively forced into the holder, means for positively pressing or forcing the band into the holder, means acting when the band has been pressed into the holder for conditioning the 25 advance end of the band so that it will adhere when the cigar is subsequently banded, and means for banding the cigar when the holder is in another position of the step by step movement of the carrier.
- 30 23. In a cigar banding machine, the combination with a cigar carrier adapted for a step by step movement and provided with holders for the bands and cigars, of a band-hopper, a feeder slide adapted to take off the bands from the hopper, one at a time, a feed roller adapted to pass the bands forwardly as they are delivered thereto, by the feeder slide, means for clamping or holding one end of the band, means for positively forcing or pressing the band into the holder to cause it to assume bent or arched condition, and means for banding the cigar after it is placed in the holder and against 40 the band.
- 45 24. In a cigar banding machine, the combination with a carrier which is adapted to move step by step, and is provided with a plurality of holders for the bands and cigars, of means for positively introducing the bands in bent or arched condition in the holders, an automatic feeder adapted to direct the cigars to the holders after the band has been placed therein, and a presser adapted to positively press or force the cigar into the holder and against the bent or arched band.
- 50 25. In a cigar banding machine, the combination with a carrier having a plurality of holders for the bands and cigars, of means for placing the bands in the holders, means for placing the cigars in the holders and against the bands, and combined followers and holders carried by the carrier 55 which are adapted to assist in banding the 65 cigar and retaining the banded cigar in the holder, and means for releasing the said followers to permit the discharge of the banded cigar.
26. In a cigar banding machine, the combination with a cigar carrier having a plurality of holders for the bands and cigars, of combined followers and holders for the respective cigar holders aforesaid comprising spring retracted movable members 70 adapted to assist in banding the cigar and to retain the banded cigar on the carrier, said combined followers and holders being adapted to operate across the cigar holders of the carrier, means for actuating said 75 combined holders and followers, and means for retaining them in holding position after the cigar has been banded until the cigar reaches discharging position on the advance 80 of the carrier.
27. In a cigar banding machine, the combination with a carrier which is adapted for a step by step movement and is provided with a plurality of holders for the bands and cigars, of combined holders and followers carried by the carrier, said followers being adapted to assist in banding the cigar and to thereafter hold the cigar on the carrier until the latter reaches discharging position, means for placing bands in the holders of the carrier, vacuum means for retaining the placed bands in said holders, means for conditioning the bands so that they will 85 adhere when the cigar is banded and cigar banding means comprising a folder and 90 holder adapted to press down one end of the band on the cigar and to hold it there, and a tucker adapted to thereafter tuck down the said held end of the band, said followers being arranged and adapted to advance 95 100 across the cigar holders of the carrier after the end of the band has been tucked and to fold down the other end of the band as fast as the tucker retreats and then to remain 105 across the cigar holder and serve as retainers to keep the banded cigars on the carrier until they reach discharging position, and means for placing cigars in the holders and against the unfolded bands prior to the action of the banding means aforesaid.
28. In a cigar banding machine, banding mechanism comprising a pair of coupled, relatively movable arms, means for swinging said arms, a spring connection between the arms adapting them to move as a unit 110 115 until the loose one of said arms is arrested, means for arresting the loose one of said arms, a pivoted folder and holder carried by the loose one of said arms, and a pivoted tucker carried by the other arm and adapted 120 to move in relation to the folder and holder.
29. In a cigar banding machine, means for banding a cigar comprising two rela-

- tively movable coupled supports, a spring connection between the supports whereby they may move as a unit until the loose one of them is arrested, means for moving said 5 supports to and fro to position them for banding, or in normal position, a folder and holder movably connected to the loose one of said supports, and a spring actuated tucker movably connected to the remaining 10 support and engaged with the folder and holder, said tucker being adapted to hold the folder down on the band and to move in relation to said holder, on the continuance of the movement after the arrest of 15 the loose one of the supports, to thereby tuck down the held end of the band.
30. In a cigar banding machine, banding mechanism comprising two relatively movable coupled supports, a spring connection 20 between the supports whereby they may move as a unit until the loose one of them is arrested, means for moving said supports

to and fro to position them for banding, or in normal position, a folder and holder carried by the loose one of said supports, and a 25 tucker carried by the remaining support, said tucker being adapted, on the continuance of its movement after the arrest of the folder and holder, to tuck down the held end of the band.

30

31. In a cigar banding machine, banding mechanism comprising a pair of coupled, relatively movable arms, means for swinging said arms, a spring connection between the arms adapting them to move as a unit until the loose one of said arms is arrested, means for arresting the loose one of said arms, a folder and holder carried by the loose one of said arms, and a tucker carried by the other arm and adapted to move in 40 relation to the folder and holder.

35

In testimony whereof I hereunto affix my signature.

ISAAC A. HARDY.
